UNITED STATES PATENT OFFICE

RALPH J. ANDERSON AND DEAN G. THOMAS, OF STOUGHTON, WISCONSIN

DESIGN FOR A CASKET LOWERING DEVICE

Application filed August 31, 1932. Serial No. 44,726. Term of patent 7 years.

To all whom it may concern:

Be it known that we, RALPH J. ANDERSON and DEAN G. THOMAS, both citizens of the United States, residing at Stoughton, in the county of Dane and State of Wisconsin, have invented a new, original, and ornamental Design for Casket Lowering Devices, of which the following is a specification, reference being had to the accompanying drawing, forming part thereof.

Figure 1 is a perspective of the casket lowering device showing our new design.

Figure 2 is a plan view of the ornamental cap shown at each of the corners of said casket lowering device.

We claim:

The ornamental design for a casket lowering device as shown.

In testimony whereof, we affix our signatures at Stoughton, Wisconsin.

RALPH J. ANDERSON.
DEAN G. THOMAS.
